E. HARRISON.

Grinding Mill.

No. 11,040.

Patented June 6, 1854.

UNITED STATES PATENT OFFICE.

EDWARD HARRISON, OF NEW HAVEN, CONNECTICUT.

GRINDING-MILL.

Specification forming part of Letters Patent No. 11,040, dated June 6, 1854; Reissued November 16, 1858, No. 625.

To all whom it may concern:

Be it known that I, EDWARD HARRISON, of the city and county of New Haven, in the State of Connecticut, have invented sundry new and useful Improvements in Grinding-Mills; and I do hereby declare that the following is a full and exact description thereof, reference being had to the accompanying drawings, making a part of this specification.

Figure 1 is a vertical section through the center of one of my improved grinding mills; Fig. 2, a bottom view of the mill; Fig. 3, a bottom view of the shoe and a portion 15 of the hopper, detached; and Fig. 4, a view of the top of the shaft.

Similar letters indicate like parts in all the figures.

I construct my improved grinding mill wholly of stone and metal, and in the strongest and most compact manner. Matched casings A and B receive the stationary grinding stone E, and the runner F, D, W. The stationary stone E, is cemented and firmly secured within the upper casing A; and the runner is rigidly secured to shaft C, and rotates freely within the lower casing B. The lower casing B, has three hollow columns H, descending from 25 its under side, upon which the mill rests; which columns are connected to each other at their lower ends by the three arm base I, &c., as shown in Fig. 2. Three standards 30 M, M', &c., rise from the upper casing A, and support the hopper K, sockets J, J, J, being cast upon the under side of the hopper which receive into them the upper ends of the said standards, as shown in Figs. 1 and 3. The shoe L, is supported and vibrated in 35 the following manner, viz:—A smooth vertical hole is formed in the rear end of the shoe, which receives the standard M, as shown in Fig. 1. A slot h is formed in the under side of the shoe, which receives into it 40 a pivot i, that rises from an eccentric position on the top of the shaft C. Consequently, it will be perceived that the rotation of the shaft, will impart the requisite vibration to the shoe. The discharge of the 45 grain from the hopper into the shoe, is governed by varying the size of its discharging aperture T, by means of the sliding gate t. The grain falls from the open end of the shoe into the open mouth of the aperture U, 50 in the upper casing, and thence it passes into the inclined passage V, in the upper

stone, which conducts it into the eye of the same. The instant that the grain falls upon the center of the runner, it is thrown outward by centrifugal force between the 60 grinding surfaces of the runner and the stationary stone; which enables the highest safe velocity to be given to the runner, without the possibility of the accumulation of grain within the eye of the stationary stone. 65

The runner is formed of a united metallic back (D) and hub (W) combined with a disk face composed of the requisite quantity and quality stone. The said back and hub of the runner, may be formed of soft metal, 70 and be cast upon the back and within the eye of a prepared stone; or be formed of cast iron, and the stone face be fitted and cemented to the back and around the hub of the same. A band α , closely embraces and 75 unites the peripheries of the metallic back and the stone face of the runner; and as the stone face wears away, the band is driven down and projects below the under side of the said back. The shaft C, is provided 80 with three bearings, viz: One in the center of each of the upper and lower casings A and B, and the step G, at its lower end. The hub-like outward projections A' and B', 85 from the centers of the casings A and B, which receive the shaft C, should be cast of such a shape as to enable them to receive bushings, or bearing surfaces, of Babbitt metal.

I give to the shaft C, a vertically elastic 90 and an adjustable bearing, by means of the following arrangement of parts; viz: The step G, of the shaft, passes down through a hole in the center of the base I, &c., and has a screw cut upon its periphery which is 95 embraced by the supporting and adjusting nut N. To the under side of the respective arms I, &c., of the base, there are secured the springs g, g, g, by means of the sustaining and adjusting screw bolts f, f, f, 100 which pass up through the said arms of the base and are arranged as shown in Figs. 1 and 2. On the inner end of each spring g, a rod c, rests and rises through a hole in the base near to the central opening in the same 105 which receives the step; and upon the upper ends of the said rods c, c, c, the nut N, rests, as shown in the drawings.

The stiffness of the springs g, g, g, can be varied by means of the screw bolts f, f, f; 110 and the shaft C, can be raised or lowered by turning the nut N. The step G, is pre-

vented from turning with the nut *N*, by means of a longitudinal groove *e*, in its side, and the screw *d*, which passes into the same, as shown in Fig. 1.

- 5 The following are some of the advantages derived from constructing the runner, of a metallic back and hub, combined with a stone grinding face, viz: The stone grinding face of the runner can be worn nearly to its 10 metallic back with perfect safety; and when it is so much worn as to be unfit for use, it can be replaced at a comparatively small expense. Second, the runner is enabled to be so rigidly and securely confined to the shaft, 15 that when placed in a metallic supporting frame the stationary stone and the runner can be truly and accurately faced by grinding them together. Third, a large sized runner can with perfect safety be rigidly 20 confined to a shaft, provided the shaft be of sufficient strength, and the hub be of sufficient height.

I am aware that a disk faced running mill stone has been supplied with a metallic 25 back and eye, when the said runner has been

suspended upon a bail and the grain fed through the eye of the same; and I am also aware that a small sized running mill stone—without a metallic back and eye—has been rigidly secured to its spindle; and therefore, I do not claim either of the said arrangements as my invention: But

What I do claim as new and desire to secure by Letters Patent, is—

An improvement in the grinding mill 35 produced by forming the runner of a metallic back and hub combined with a disk grinding face composed of the requisite quantity and quality of stone, and, rigiding securing the shaft within the metallic hub of the runner, when the said runner is arranged and operates with the stationary uppermost stone substantially as herein set forth.

The above specification of my improvement in grinding mills signed and witnessed 45 this 27th day of January, 1853.

EDWARD HARRISON.
